Primary Examiner — Natasha Vujcic(74) *Attorney, Agent, or Firm* — Wood IP LLC(57) **CLAIM**

The ornamental design for a light fixture, as shown and described.

DESCRIPTION

FIG. 1 is a perspective view of a light fixture in accordance with the present design;
FIG. 2 is a front view thereof;

FIG. 3 is a right side view thereof, wherein a left side view is the mirror image thereof;

FIG. 4 is a top view thereof; and,

FIG. 5 is a bottom view thereof.

The broken lines in the drawings illustrate portions of the light fixture which form no part of the claimed design.

1 Claim, 5 Drawing Sheets(56)
